DESIGN FOR A DOUCHE NOZZLE

George H. Shrodes, Los Angeles, Calif.

Application January 19, 1934, Serial No. 50,456

Term of patent 3½ years

To all whom it may concern:

Be it known, that I, GEORGE H. SHRODES, a citizen of the United States, residing at Los Angeles, in the county of Los Angeles and State of California, have invented a new, original, and ornamental Design for a Douche Nozzle, of which the following is a specification, reference being had to the accompanying drawing, forming part thereof.

Fig. 1 is a perspective view of a douche nozzle, showing my new design;

Fig. 2 is a plan view; and

Fig. 3 is an elevational view.

I claim:

The ornamental design for a douche nozzle, as shown.

GEO. H. SHRODES.
